CLOTHES HAMPER

E. Burton Benjamin, Chicago, Ill., assignor to Quaker Stretcher Company, Kenosha, Wis., a corporation of Wisconsin

Application April 13, 1959, Serial No. 55,481

Term of patent 14 years

(Cl. D58—4)

Fig. 1 is a front perspective view of a clothes hamper embodying my new design;

Fig. 2 is a front elevational view thereof;

Fig. 3 is a side elevational view thereof; and

Fig. 4 is a plan top view thereof.

The dominant features of my design reside in the portions shown in solid lines.

I claim:

The ornamental design for a clothes hamper, as shown and described.
